(No Model.)

X. VIGER.
Mail Bag Fastening.

No. 241,096.

Patented May 3, 1881.

UNITED STATES PATENT OFFICE.

XYSTE VIGER, OF LONGUEUIL, QUEBEC, CANADA.

MAIL-BAG FASTENING.

SPECIFICATION forming part of Letters Patent No. 241,096, dated May 3, 1881.

Application filed January 25, 1881. (No model.) Patented in Canada December 11, 1880.

To all whom it may concern:

Be it known that I, XYSTE VIGER, of Longueuil, in the Province of Quebec, Canada, have invented an Improvement in Fastenings for 5 Mail-Bags, of which the following is a specification.

This fastening consists of a strap that is made with tongues to enter eyes upon the front of the bag and prevent the flap being raised. 10 The eyes pass through openings in the flap, and also through openings in the strap adjacent to the tongues, and when the strap is moved in one direction the tongues pass through the eyes and secure the flap, and when 15 moved in the other direction the tongues are withdrawn and the flap can be raised. The strap is retained in place upon the flap by a box or case, and the strap is locked to place by a padlock, the hasp of which passes through 20 an eye on the flap projecting through an opening in the strap.

In the drawings, Figure 1 is an elevation of a mail-bag with my improved fastening applied thereto. Fig. 2 is a vertical section at 25 the line *xx*, Fig. 1. Fig. 3 is a horizontal section at the line *yy*, Fig. 2. Fig. 4 shows the strap detached. Fig. 5 is an elevation of the rear of the box for the strap. Fig. 6 represents one of the eyes for the locking-tongue, 30 and Fig. 7 is a section of the flap adjacent to one of these eyes.

The mail-bag is made in the usual manner, with the front *a*, back *b*, sides *c*, bottom *d*, and flap *e*, and upon the front of the bag the 35 eyes *h* are fastened, said eyes being formed of wire in the shape shown in Figs. 6 and 7. The semicircular shanks or heads of these eyes are between the body of the bag and a strip of leather that is sewed to said bag, the eyes 40 passing through mortises in the strip, and projecting above the surface thereof. The flap *e* has mortises through it in positions corresponding to the eyes *h*, so that said flap may be closed tightly against the face of the mail- 45 bag, and the eyes will project through said flap. *i* is the locking-strap, slightly longer than the width of the bag, and this strap slides freely within the box or case *k*, that is secured to the front of the flap. This case is made 50 with a top piece, having mortises *u*, corresponding to the mortises in the flap *e*, and there is a cover or cap over the top, and the parts are

sewed or otherwise firmly connected together and to the flap *e*. Portions of the strap *i* are cut out to form the tongues *l*, and leave the 55 necessary opening adjacent to each tongue for the eyes *h* to pass through. If the strap *i* is made of leather, one or both sides of each tongue should be faced with metal, *m*, to 60 strengthen it.

Before closing the flap *e* the strap *i* is moved endwise until the openings at the ends of the tongues are in line with the openings in the flap. Then the flap is pressed down against the front *a* of the bag, and the eyes *h* pass 65 into the openings in the case and through the said strap. The strap is then pulled endwise, and the tongues *l* enter said eyes and securely hold the flap. The strap is locked in place by the eye *t* being passed through a mortise in 70 the strap, and a padlock applied at this eye *t*.

The box and the strap may be made of leather or metal, as desired, and the fastening may be used for other articles than mail- 75 bags.

I am aware that mail-bag fastenings have been made with an endwise-moving strap having tongues that pass into eyes, and that this strap has been locked into its place. By my improvement the box or case incloses the end-moving strap, and it also supports the eyes in 80 position for the tongues of the strap to pass through them, and it prevents access to the strap, tongues, or eyes when the bag is closed, thus increasing the security. 85

I claim as my invention—

1. The locking-strap *i*, with tongues *l* and openings adjacent thereto, in combination with the box or case *k* upon the flap *e*, and the eyes *h* and *t* upon the front *a* of the bag, the eye *t* being adapted to receive the lock, substantially as and for the purposes set forth. 90

2. The eyes *h*, made with semicircular ends, and the mortised strip by which the eyes are secured to the mail-bag, in combination with the flap *e*, case *k*, and strap *i*, sliding within 95 the case, and having tongues that pass into the eyes *h*, substantially as set forth.

Longueuil, December 30, 1880.

XYSTE VIGER.

In presence of—

A. LÉVÈQUE,
J. W. LESPÉRANCE.
